NONSLIP ATTACHMENT FOR SHOES

Katharine Lee Jones, Kansas City, Mo.

Application December 7, 1939, Serial No. 308,000

6 Claims. (Cl. 36—7.7)

My invention relates to improvements in non-slip attachments for shoes. It is particularly adapted for application to the bottom of the front portion of the sole of the shoe, and for use on icy surfaces, or for golf use.

One of the objects of my invention is the provision of a novel calked pad for application to the sole of a shoe, and which is cheap to construct, is durable, has a pleasing appearance, is particularly well adapted for application and use on a woman's shoe without liability of injury thereto.

A further object is to provide novel means for releasably attaching the device to the shoe, which is easily and quickly operated to fasten or unfasten, and which will reliably hold the device attached to the shoe, and is efficient in operation.

The further object of my invention is to provide novel means for engaging the upper edge of the rear end of the shoe for holding a fastening strap embracing said rear end from downward slipping and may be adjusted to suit shoes of different sizes.

The novel features of my invention are hereinafter fully described and claimed.

In the accompanying drawing, which illustrates my invention,

Fig. 1 is a side elevation of my improved attachment applied in operative position on a woman's shoe.

Fig. 2 is an enlarged under view, partly broken away, of the attachment.

Fig. 3 is a section on the line 3—3 of Fig. 2.

Fig. 4 is a perspective of one form of hook member for releasably engaging the upper edge of the rear of the shoe, and which is slidably adjustable on the strap embracing the rear end of the shoe, for holding said strap from downward slipping.

Fig. 5 is a perspective view of another form of hook of my invention, shown mounted on a portion of the strap.

Similar characters of reference designate similar parts in the different views.

For application to the bottom of the front portion of the sole of a shoe, there is provided a flat plate like member consisting of two small leather sheets 1 and 2 disposed one above the other and sewed together adjacent to their edges by stitching 3.

The leather pieces 1 and 2 have a width slightly less than the shoe sole 4 to which the device is to be attached, and extends over that portion of the sole under the ball of the foot.

Between the two sheets or pieces of leather 1 and 2 are disposed the heads 5 of calks having

stems 6 extending through and projecting from the lower sheet 2, the lower ends of the stems 6 being, preferably, pointed to have nonslip engagement with the surface with which they have engagement when in use.

A transverse strap 7 is mounted between the leather sheets 1 and 2 to which the strap is attached by the stitching 3. The end portions of the strap 6 respectively project from the side edges of the sheets 1 and 2, said strap being disposed adjacent, preferably, to the front ends of the sheets 1 and 2. Said projecting end portions of the strap 7 are adapted to embrace the front upper portion of the shoe, the latter being designated generally by 9.

The strap end portions have means for being releasably fastened together, such means, as shown, being a buckle 10 attached to one end of the strap 7, and adapted for engagement with the other end portion of the strap.

Two rearwardly diverging straps 11 and 12 have their front end portion disposed between the sheets 1 and 2, to which they are attached by the stitching 3, at opposite sides of the longitudinal center of the sheets 1 and 2, which are of like size and shape.

The strap 11 is of a length such that it will embrace the rear end of the shoe adjacent to the upper edge thereof, as shown in Fig. 1. The straps 11 and 12 have suitable means for releasably fastening them together, which, as shown consist of a buckle 13 attached to the free end of the strap 12, and which is adapted for engagement with the free end portion of the strap 11 in the usual manner.

For holding the strap 11 from downward slipping it has mounted on it, preferably slidably a hook member adapted to fit over the upper edge of the rear end of the shoe. I have shown two forms of such hook members. In Figs. 1, 2 and 3, the hook member shown therein consists of a metal plate 14 having at its opposite side edges two rearwardly extending ears 15 each having therethrough a hole or vertical slot 16, the slots being transversely aligned, and the strap 11 being slidably extended through said slots. The upper end portion of the plate 14 is reversely turned to form a hook 17 adapted to have its downwardly turned end portion enter the shoe, whereby the hook rests upon the upper edge of the rear end of the shoe which is snugly embraced by the hook 17.

To limit the range of sliding adjustment of the hook member and to hold it from accidentally being disengaged from the strap 11, said strap

is provided with two lateral projections, which may be small buttons 18, disposed spaced from and at opposite sides of the hook member 14.

Another form of hook member is shown in Fig. 5, which comprises a plate 19 having through it two transversely aligned vertical slots 20 through which extends the strap 11, the strap being disposed with its opposite sides bearing against opposite sides of the plate 19, whereby the strap 11 10 is slightly deformed, so that the plate 19 exerts a slightly gripping action, and is thus held from accidental sliding. The upper portion of the plate 19 is reversely turned to form a hook 21, which is adapted to engage the upper edge of the 15 rear end of the shoe, after the manner of such engagement as was described with reference to the hook 17.

In applying the device to a shoe, the calked pad member has its upper sheet 1 disposed against the under side of the front portion of the sole 4, and the end portions of the strap 1 are passed over the front portion of the shoe, tightened and fastened together by means of the buckle 10.

25 The straps 11 and 12 are then coupled together by means of the buckle 13, the strap 11 being passed around the rear end of the shoe, adjacent to the upper edge thereof, the hook 17, or the hook 21, as the case may be, being made to engage the upper edge of the rear end of the shoe. The straps 11 and 12 are then drawn together tightly, which thus securely fastens the device upon the shoe.

With the use of the hook member 19, after once 35 being adjusted its clamping effect on the strap 11 will retain it in its operative position. It may be readily slipped, however, to such operative position.

When not in use a pair of these devices may 40 have their straps folded over the calked pad, and be stored, when not in use, in a small container, not shown, which may be carried in a pocket or small purse.

Other modifications of my invention, within 45 the scope of the appended claims, may be made without departing from the spirit of my invention.

What I claim is:

1. A nonslip attachment for a shoe comprising 50 a flat plate like member having a smooth upper surface adapted for application to the bottom of a front portion of the sole of the shoe, and having calks projecting from the under side of said member, a transverse strap attached to the front 55 portion of said member and having portions projecting respectively from opposite side edges of said member and adapted to embrace the upper front portion of the shoe, said strap having means for releasably fastening together said projecting portions, two rearwardly extending straps fastened at their 60 front ends to the rear end of said member, one of which two straps is adapted to embrace the rear end of the shoe adjacent to the upper edge thereof, said two straps having means for releasably fastening together their free end portions, and a hook 65 slidably mounted upon said rear end embracing strap and adapted to releasably engage the upper edge of the rear end of the shoe.

2. A nonslip attachment for a shoe comprising 70 a flat plate like member adapted for application of its upper side to the bottom of a front portion of the sole of a shoe, and having calks projecting from its under side, a transverse strap attached to said member and having portions projecting 75 respectively from opposite side edges of said

member and adapted to embrace the upper front portion of the shoe, and having means for releasably fastening together said projecting portions, two rearwardly extending straps fastened at their front ends to said member, one of which two straps is adapted to embrace the rear end of the shoe adjacent to the upper edge thereof, said two straps having means for releasably fastening together their free end portions, and a hook 10 slidably mounted upon said rear end embracing strap and adapted to releasably engage the upper edge of the rear end of the shoe.

3. A nonslip attachment for a shoe comprising a flat plate like member adapted for application to the bottom of a front portion of the sole 15 of a shoe, and having calks projecting from its under side, a transverse strap attached to said member and having portions respectively projecting from opposite side edges of said member and adapted to embrace the upper front portion 20 of the shoe and having means for releasably fastening together said projecting portions, two rearwardly extending straps fastened at their front ends to said member, one of which two straps is adapted to embrace the rear end of the 25 shoe adjacent to the upper edge thereof, said two straps having means for releasably fastening together their free end portions, said rear end embracing strap having a lateral projection, and a hook 30 slidably mounted upon said rear end embracing strap between said projection and the outer end of the last named strap and adapted to releasably engage the upper edge of the rear end of the shoe.

4. A nonslip attachment for a shoe comprising 35 a flat plate like member adapted for application to the bottom of a front portion of a sole of a shoe, and having calks projecting from the under side of said member, a transverse strap attached to said member and having portions respectively 40 projecting from opposite side edges of said member and adapted to embrace the upper front portion of the shoe and having means for releasably fastening together said projecting portions, two rearwardly extending straps fastened at their 45 front ends to said member, one of which two straps is adapted to embrace the rear end of the shoe adjacent to the upper edge thereof, said two straps having means for releasably fastening together their free end portions, said rear end 50 embracing strap having two lateral projections, and a hook 55 slidably mounted upon said rear end embracing strap between said projections and adapted to releasably engage the upper edge of the rear end of the shoe.

5. A nonslip attachment for a shoe comprising a flat plate like member adapted for application to the bottom of a front portion of the sole of a shoe, and having calks projecting from the under side of said member, a transverse strap attached 60 to said member and having portions respectively projecting from opposite side edges of said member and adapted to embrace the upper front portion of the shoe and having means for releasably fastening together said projecting portions, two 65 rearwardly extending straps fastened at their front ends to said member, one of which two straps is adapted to embrace the rear end of the shoe adjacent to the upper edge thereof, said two straps having means for releasably fastening together their free end portions, and a plate having 70 two transversely aligned slots through which extends said strap which embraces the rear end of the shoe, said plate having a downwardly turned hook adapted to engage the inner and 75

outer sides of the upper edge of the rear end of the shoe.

6. A nonslip attachment for a shoe comprising a flat plate like member adapted for application at its upper side to the bottom of a front portion of the sole of a shoe, and having calks projecting from the under side of said member, a transverse strap attached to said member and having portions projecting from opposite side edges of said member and adapted to embrace the upper front portion of the shoe and having means for releasably fastening together said projecting portions, two rearwardly extending straps fastened at their front ends to said member, one of which two

straps is adapted to embrace the rear end of the shoe adjacent to the upper edge thereof, said two straps having means for releasably fastening together their free end portions, and a plate having two transversely aligned slots and having its upper end reversely turned to form a hook 5 adapted to releasably engage the upper edge of the rear of the shoe, said strap which embraces the rear end of the shoe being extended through said two slots with its opposite sides respectively 10 bearing against the front and rear sides of said plate.

KATHARINE LEE JONES.
